DELIVERY HEATER FOR PRINTING PRESSES

Filed Feb. 27, 1925

2 Sheets-Sheet 2

UNITED STATES PATENT OFFICE.

CHARLES BRADLEY, OF LOS ANGELES, CALIFORNIA.

DELIVERY HEATER FOR PRINTING PRESSES.

Application filed February 27, 1925. Serial No. 11,962.

To all whom it may concern:

Be it known that I, CHARLES BRADLEY, a citizen of the United States, residing at Los Angeles, in the county of Los Angeles and State of California, have invented certain new and useful Improvements in Delivery Heaters for Printing Presses, of which the following is a specification.

This invention is a heater for the printed sheets from a press, and it is the object of the invention to automatically shut-off the heater when the press is tripped, and to again supply the heat as soon as the trip is released.

The heater is particularly adapted for a two-revolution cylinder press operating with face-up delivery; and it is the specific object of the invention to provide a heater which may be removably mounted on the carriage of the sheet delivery mechanism, and having a control adapted to be turned on and off by operation of the fountain trip of the press.

Further objects of the invention will be readily understood from the following description of the accompanying drawings in which:

Fig. 1 is a perspective view of the delivery mechanism of a press, showing the heater mounted thereon.

Fig. 2 is a side elevation of the heater control mechanism, showing the same when the trip of the press is released.

Fig. 3 is a similar view showing the position of the parts when the press is tripped.

Fig. 4 is a vertical section on the line 4—4 of Fig. 2.

Fig. 5 is a perspective view of the heater.

I have shown the heater mounted upon a standard two-revolution cylinder press, the heater being supported by the fly stick rod of the delivery mechanism so as to heat the printed sheets as they pass to the jogger board of the press. The heater is shown as a gas-burner pipe extending the width of the delivery carriage, and having a valvular control which is operated by a cam mechanism fixed to the fountain trip connecting rod of the press.

A usual delivery mechanism for a press is shown as comprising delivery ways 1 with carriage 2 adapted to move back and

forth thereon, the carriage being operated by usual levers 3 and link connections 4. Rod 5 of the carriage supports the fly sticks 6, to which the printed sheets are delivered faceup from the tapes 7 as the fly sticks move outwardly toward the jogger board 8 of the press.

Stop fingers 9 mounted on a rod 10 of the carriage hold the printed sheets on the fly sticks until the latter are above the jogger board, and then release the sheets to permit delivery thereof to said board by the action of pusher fingers 11 as the carriage moves inwardly. The pusher fingers are mounted in usual manner upon a transverse rod 11^a of the delivery carriage.

The fountain box 12 is mounted below the jogger board, and the fountain ratchet lever 13^a is operated in usual manner by the connecting rod 13 which extends along the gear side of the press. The fountain trip is operated by cam 14^a which is connected to trip rod 15 extending along the gear side of the press; and depression of the usual foot pedal (not shown) is adapted to trip the press in usual manner to allow reciprocation of the bed without contact of the printing form with the cylinder and also shift rod 16 to operate the fountain trip. Rod 15 is also depressed as it is shifted longitudinally, due to the limited movement of the arm 14^a of the trip cam from the position shown in Fig. 2 to that shown in Fig. 3.

The improved heater for the sheet delivery is shown as a pipe 16 removably supported by brackets 17 from fly stick rod 5, and extending the width of the press in front of said rod. Gas is preferably used as a heating medium, the pipe 16 being provided with burner apertures 18 along its outer side; and a shield or baffle strip 19 preferably extends over the top of pipe 16 in spaced relation above the burners to protect the printed sheets and also prevent extinguishing of the burners by the formation of air pockets.

The end of pipe 16 at the feeder side of the press is preferably closed by a cap 20, and gas is supplied to the pipe at the opposite or gear side of the press through a pipe connection 21. The pipe connection extends upwardly over the delivery way 1 and carriage 2, and along the outer side of the de-

livery way, so as to permit movement of the heater with the delivery carriage without striking the stationary parts of the press. The pipe 21 is preferably supported by a bracket 22 detachably fixed to the carriage 2.

An air mixer 23 is provided in the pipe 22 and is regulated by a slidable sleeve 24. Gas is supplied through a flexible tubing

- 10 25 to a pipe 26 which is connected to a regulating valve 27 having a manual control 27^a; and a stop-cock 28 is provided between valve 27 and the air mixer 23. A tube 29 leads from the casing of valve 27 and along 15 pipe 21 to the burners 18, where it forms a pilot burner 30 shielded by a guard 31 on the burner pipe. The supply of fuel through tube 29 is regulated by a valve in casing 27 having a manual control 29^a.
- 20 Stop-cock 28 which controls the supply of fuel to the burners 18 is turned on and off by a usual rotatable plug 32 having a cross head 34 for operating the same. The cross head is turned for opening or closing the 25 stop-cock by cam mechanism cooperating with rollers 33 journaled on the ends of the head.

The cam mechanism is adapted to be shifted into the path of the rollers for turning 30 the cross head as the heater structure is moved back and forth with carriage 2, stop-cock 28 being open so that the burners are lighted when the cross head is horizontal, and being turned to closed position for extinguishing the burners by turning of the 35 cross head to vertical position. During normal operation of the press with the trip released the cam mechanism is out of the path of travel of rollers 33, but is shifted 40 into said path of travel so as to turn the cross head 34 by the tripping of the press.

For this purpose the cam mechanism is preferably mounted on the fountain trip connecting rod 15, the movement of which 45 as the press is tripped or released shifts said cam mechanism into operative or inoperative position. As an instance of this arrangement an arm 35 is detachably clamped on rod 15 as shown at 36, and is preferably 50 braced by an arm 35^a clamped to the rod 15 and the arm 35. An open frame 37 is supported by arm 35 with the valve mechanism of the heater structure adapted for movement back and forth through said 55 frame; and fingers 38 on the frame are preferably slidably mounted in a guide 39 on delivery way 1, to hold the frame in position during shifting thereof with the fountain trip connecting rod.

60 Cams 40 and 41 are mounted in the respective ends of frame 37, the cam 40 comprising surfaces 40^a in alinement with the respective rollers 33 and curving upwardly and downwardly respectively to a vertical 65 end abutment surface 40^b; and the cam 41

comprising a horizontal surface 41^a of a width to aline with both rollers 33, and having downwardly inclined ends 41^b adapted for engagement by the respective rollers.

In normal operation of the press with the trip released, rod 15 is shifted to its limit of movement toward the delivery end of the press as shown in Fig. 2, thereby moving cam 40 beyond the limit of movement of cross head 34 as the latter is moved back and forth with the delivery carriage of the press, and positioning cam 41 so that the rollers 33 will pass over the same without contact with inclined surfaces 41^b, when the cross head is in horizontal position. The 75 heater will thus continue to burn throughout normal operation of the press.

When the press is tripped, connecting rod 15 is shifted in the opposite direction as shown in Fig. 3, thereby shifting cam 40 so that its vertical abutment surface 40^b and its curved surfaces 40^a are within the limit of movement of the horizontally disposed cross head as the latter is moved back and forth with the delivery carriage. As a consequence one or the other of rollers 33 will ride upon its cooperating curved surface 40^a and thence along vertical abutment surface 40^b so as to turn the cross head to vertical position, the surface 40^b being at the end of the limit of movement of the cross head when the latter is thus vertically positioned. The turning of the cross head closes stop-cock 28 as previously described, and thus extinguishes burners 18.

Tripping of the press as thus described, also lowers rod 15 as shown in Fig. 3, thereby shifting cam 41 below the path of travel of the vertically disposed cross head as the latter continues to move back and forth with the delivery carriage, so that rollers 33 are out of contact with cam 41 and thus permit the cross head to remain in vertical position for closing of stop-cock 28 and extinguishing of the burners of the heater, 100 as long as the press remains tripped.

When the press is again released from tripped position, rod 15 is returned to its normal position, thereby again moving cam 40 beyond the limit of movement of the cross head, and shifting cam 41 upwardly as shown in Fig. 3, so that one or the other of the rollers on the vertically positioned cross head will ride upon its cooperating inclined surface 41^b as the cross head moves back and forth with the delivery carriage, and thereby turn the cross head back to horizontal position.

Stop-cock 28 is thus reopened so that the burners 18 are lighted by pilot 30; and the cross head will then remain in horizontal position as it is moved back and forth, so that the heater will continue to burn until the press is again tripped, since with the cross head in horizontal position, cams 40 and 41

are both in inoperative position outside of the path of travel of rollers 33, as shown in Fig. 2 and as previously described.

I claim:

- 5 1. A heater for a printing press having trip mechanism and a movable delivery carriage, comprising heating means mounted on said carriage, a control for said heating means moving with the latter and said carriage, and means for operating said control connected to the trip mechanism of the press so as to shut-off and operate said heater as the press is tripped and released respectively.
- 10 2. A heater for a printing press having a movable delivery carriage, said heater comprising heating means mounted on said carriage, a control for said heating means moving with the latter and said carriage, and operating means for said control shifted relative to the path of movement thereof by the tripping and release of the press so as to shut-off and operate the heater as the press is tripped and released respectively.
- 15 3. A heater for a printing press having a fountain trip connecting rod and a movable delivery carriage, said heater comprising heating means mounted on said carriage, a control for said heating means moving with the latter and said carriage, and operating means for said control shifted relative to the path of movement thereof by the tripping and release of the press so as to shut-off and operate the heater as the press is tripped and released respectively.
- 20 4. A heater for a printing press having a fountain trip connecting rod and a movable delivery carriage, said heater comprising heating means mounted on said carriage, a control for said heating means moving with the latter and said carriage, and operating means for said control shifted relative to the path of movement thereof by the tripping and release of the press so as to shut-off and operate the heater as the press is tripped and released respectively.
- 25 5. A heater for a printing press having a fountain trip connecting rod and a movable delivery carriage, said heater comprising heating means mounted on said carriage, a control for said heating means moving with

the latter and said carriage, and operating means for said control mounted on the fountain trip connecting rod of the press and shifted relative to the path of movement of said control by movement of the fountain trip connecting rod as the press is tripped or released, so as to shut-off and operate the heater respectively.

4. A heater for a printing press having a movable delivery carriage, said heater comprising heating means mounted on said carriage, a control for said heating means moving with the latter and said carriage, cams adapted for respective engagement with said control so as to actuate the same for shutting-off and operating the heater, and means for moving the respective cams into the path of travel of said control by tripping and releasing of the press.

5. A heater for a printing press having control mechanism and a movable carriage, said heater comprising heating means mounted on the carriage, and means for shutting-off and operating said heating means by actuation of said control mechanism.

In testimony whereof I have affixed my signature to this specification.

CHARLES BRADLEY.
